PROCESS FOR PREPARING COMPOSITE
NEGATIVES FOR USE IN THE PRODUC-
TION OF PHOTOGRAVURE AND ROTO-
GRAVURE PRINTING FORMS

Stanley John Verriour, Watford, England

No Drawing. Application May 31, 1939, Serial No.
276,558. In Great Britain May 31, 1938

4 Claims. (Cl. 95—5)

The invention relates to processes for preparing composite positive transparencies containing both pictorial and line or type matter for use in the production of photogravure and rotogravure printing forms, and it is more particularly concerned with a process for the production of paper negatives for planning to obtain the desired composite negatives from which the composite originals are produced.

It is usually necessary to plan both type or line matter and pictorial matter in the obtaining of the desired composite negative. In order to carry out the planning operation with simplicity and speed, it has been found desirable to employ paper negatives on a black ground, the negatives being partly pictorial matter and partly line or type matter. The paper negatives of pictorial matter are produced photographically whilst the type or line negatives are produced by first preparing a pull from set-up type or line matter, and then photographing the pull on the paper that it is desired to use in the planning. It will, of course, be appreciated that in distinguishing between "pictorial" and "type or line" matter it is assumed that pictorial matter is of a nature which cannot be readily reduced to line or type and cannot, therefore, be readily set up and a pull taken therefrom.

It will be observed that in obtaining a paper negative for the planning stage, of the type or line matter, the indirect method is employed of first obtaining a pull and then photographing the pull. It is an object of the invention to dispense with the necessity of employing a camera to obtain the paper negative from the pull. In accordance with the invention a composite positive transparency containing both pictorial and line or type matter for use in the production of photogravure and rotogravure printing forms, is prepared by producing upon a transparent or translucent carrier, relatively opaque impressions of the type or line matter, and preparing from the resulting carrier a contact print on sensitised paper, thereby to secure a paper negative of the type or line matter. The paper print thus produced then has combined with it, by planning, a paper negative of the pictorial matter, thereby to obtain a composite paper negative, this composite negative being photographed on to a sensitised plate or film to obtain the desired composite positive transparency.

In carrying the invention into effect, various kinds of translucent carriers may be used. In particular, a very light flexible carrier may be employed such as, for example, cellulose skin or

the material known under the registered trademark "Cellophane." It is unimportant what kind of ink is employed in making the pull upon the Cellophane or other translucent carrier, that is to say whether the ink is black or white. It is necessary only that the ink shall be relatively opaque so that a contact may be made from the resulting pull with the aid of sensitised paper.

It is advantageous to employ sensitised paper which, in the resulting paper negative, gives a light colour on black instead of a pure white on black. Thus, in carrying the present invention into effect a tinted sensitised paper may be employed.

In the above, reference has been made to the production of a pull upon a transparent carrier. It is to be understood that the carrier bearing relatively opaque impressions may be made from a bank of set-up type or may be produced in a machine in which an impression is made from a single type face or a line of type faces. Alternatively, the impression may be produced photographically with, for example, the aid of a photographic type-composing machine.

What I desire to claim and secure by Letters Patent in the United States is:

1. A process for preparing a composite positive transparency containing both pictorial and line or type matter for use in the production of photogravure and rotogravure printing forms, comprising the production upon a carrier capable of passing light, of relatively opaque impressions of the type or line matter, preparing from the resulting carrier a photographic contact print on sensitised paper, thereby to secure a paper negative of the type or line matter, combining with the said print, by planning, a paper negative of the pictorial matter, thereby to obtain a composite paper negative, and photographing the said composite negative on to a sensitised transparent base which gives the composite positive transparency.

2. A process for preparing a composite positive transparency containing both pictorial and line or type matter for use in the production of photogravure and rotogravure printing forms, comprising the production upon a carrier capable of passing light, of relatively opaque impressions of the type or line matter, preparing from the resulting carrier a photographic contact print on a tinted sensitised paper so as to obtain a paper negative consisting of line or type matter in light colour on black, combining with the said print, by planning, a paper negative

of the pictorial matter, thereby to obtain a composite paper negative, and photographing the said composite negative on to a sensitised transparent base which forms the composite positive transparency.

3. A process for preparing a composite positive transparency containing both pictorial and line or type matter for use in the production of photogravure and rotogravure printing forms, comprising the production typographically upon a transparent carrier of relatively opaque impressions of the line or type matter, preparing from the resulting carrier a photographic contact print on sensitised paper, thereby to secure a paper negative of the line or type matter, combining with the said print, by planning, a paper negative of the pictorial matter, thereby obtaining a composite paper negative, and photographing the said negative on to a sensitised transparent plate to produce the composite positive transparency.

4. A process for preparing a composite positive transparency containing both pictorial and line or type matter for use in the production of photogravure and rotogravure printing forms, comprising the production on a transparent carrier of relatively opaque impressions of the line or type matter, preparing from the resulting carrier a photographic contact print on tinted sensitised paper, thereby securing a paper negative in which the line or type matter appears light on a dark background, combining with the said print, by planning, a paper negative of the pictorial matter which also appears light on dark background, thereby to provide a composite paper negative, and photographing this negative on to a sensitised transparent base which is developed to provide the desired composite positive transparency.

STANLEY JOHN VERRIOUR. 20
